(57) **CLAIM**

The ornamental design for a coffee pod carousel, as shown and described.

DESCRIPTION

FIG. 1 is a perspective view of a coffee pod carousel showing my new design;

FIG. 2 is a front view thereof;

FIG. 3 is a top view thereof; and,

FIG. 4 is a bottom view thereof.

A rear view, a left view and a right view are omitted since the rear view, the left view and the right view are identical with the front view.

The broken lines depict portions of a coffee pod carousel in which the design is embodied that form no part of the claimed design.
